GARMENT CONSTRUCTION

Stanley J. Latker, Los Angeles, Calif.

Application September 19, 1958, Serial No. 762,036

4 Claims. (Cl. 2—106)

This invention relates to garments, and particularly to an improved construction for upper garments, such as blouses, shirts, etc.

Garment constructions for blouses, shirts, and other similar wearing apparel, have been made in an attempt to enable the arms of the wearer to be raised above the head without causing the blouse or shirt to be withdrawn from its normal position at the waistline. These prior constructions have had additional material located at the arm holes, such as shown in Johnson Patent No. 2,825,067 of March 4, 1958.

The present invention is a construction which not only satisfactorily permits the arms to be raised above the head without moving the waistband portion of the upper garment from the waistline, but also provides for free body movements without disturbing the lower portion of the garment. These results have been achieved by providing extra length to the garment by creating a pleat or tuck above the waistline, the pleat or tuck providing a contoured band around the waistline. By the use of darts to provide contouring and to remove extra material of the blouse or shirt at the proper points, the garment returns to its original attractive appearance after the arms are lowered and the upper portion of the body returns to its normal position.

The principal object of the invention, therefore, is to provide an upper garment construction which is attractive and permits arm and body movements without changing the position of the waistband of the upper garment with respect to a lower garment.

Another object of the invention is to provide an improved upper garment construction having an expandable lower portion which prevents the waistband or tail of an upper garment from being removed from the waistband of a lower garment, the upper garment always returning to its original attractive appearance.

A better understanding of this invention may be had from the following detailed description when read in connection with the accompanying drawings, in which:

Fig. 1 is a front perspective view of a lady's garment, such as a blouse, embodying the invention;

Fig. 2 is a side elevational view of the garment of Fig. 1 showing it in expanded position;

Fig. 3 is a back view of a back portion of the blouse showing one step in the construction of the garment;

Fig. 4 is a view similar to Fig. 3 showing a succeeding step in the construction of the garment.

Fig. 4a is a detailed view showing the formation of one of the darts used in the construction of the blouse;

Fig. 5 is a side elevational view of the back portion of the garment shown in Figs. 3 and 4;

Fig. 6 is a detailed cross-sectional view showing the lower pleat or fold of the garment and taken along the line 6—6 of Fig. 4;

Fig. 7 is a front view of front portions of the garment similar to Fig. 3 showing another step in the construction of the garment;

Fig. 8 is a view showing the portions of Fig. 7 after the darts have been sewed;

2

Fig. 9 is a side elevational view of one of the front portions of the garment shown in Fig. 8; and

Fig. 10 is a detailed cross-sectional view showing the lower pleat or fold and taken along the line 10—10 of Fig. 9.

Referring, now, to the drawings in which the same reference numerals identify like elements, a lady's blouse is shown constructed of a back portion 5, a waistband or belt portion being shown at 6, which is to be sewn to the back section 5. In the section 5 is a plurality of darts, the end darts such as 8 and 9 being diamond-shaped, while the other darts 10 have substantially lower parallel portions together with upper pointed portions. The diamond-shaped darts are to give the contour effect, while the intermediate darts are to take out the excess material to properly fit the upper edges of the waistband 6. Along the longitudinal axes of the darts shown by the center phantom lines 12, the darts are folded and then sewn along the outer solid lines as shown in Fig. 4a. The central portion of the darts is then folded over as is shown in the side elevational view in Fig. 5.

After the center sections 12 have been pressed against the body of the portion 5, the upper edge of the waistband 6 is sewn to the lower edge 14 of the section 5, as shown at 15. The lower portion of the section 5 is now folded at a position indicated by the phantom line 17, to form a slight loop as shown in Fig. 6.

Referring, now, to Figs. 7 to 10, inclusive, two front sections of the garment are shown at 20 and 21, these sections having similar darts 22 and 23, respectively, and large bust darts 25 and 26 used in ladies' garments. These garments are also provided with respective waistbands 28 and 29. The darts 22, 23, 25, and 26 are folded along their longitudinal axes as shown by phantom lines 27 and 28, and then sewn along the solid lines of the darts as described above for Fig. 3. Fig. 8 shows the sections 20 and 22 after the darts have been sewed, and a side elevational view of the sewed section 20 is shown in Fig. 9. Similar to Figs. 3, 4, and 5, the sections 20 and 21 are sewn along their lower edges to the respective waistbands 28 and 29. The body portion is now folded along the phantom lines 31 and 32 as shown in Fig. 8, Fig. 10 showing the finished effect, while the completed garment is shown in Figs. 1 and 2.

Although the invention has been illustrated as a lady's blouse, a man's shirt or similar garment may be constructed in the same manner without a waistband. It is understood, of course, that the sections 5, 20, and 21 are sewed together in the usual manner to complete the blouse.

To illustrate a specific garment, the back section is measured from the cervical or back neck point 33 (see Fig. 1) to the natural waistline 34. For example, if this measurement is 16 inches, we deduct approximately 1½ inches, which is usually the width of the waistband of a trouser or skirt. Because a trouser or skirtband is constructed to go above the natural waistline, the blouse should be approximately 1½ inches shorter so that this band will show and not be covered by the blouse. This means the back length of the blouse to the folded edges will be 14½ inches.

By the above described construction, the fold line 17 forms a contour as it encircles the body and runs parallel with the contoured waistline, which is accomplished by the darts described above. The darts are used with any style of garment. Now, from the 14½ inch point, there must be added a sufficient length of cloth where it turns upward so that it can meet and be sewed to the upper edge of the band 6 as shown in Fig. 3. If the bands 6, 28, and 29 are approximately 3 inches wide, and the blouse where it turns upward is 14½ inches, or 1½ inches from the waistline, then approximately

1½ inches must be added to 14½ inches to create an expandable 3 inch pleat, which is usually the right amount needed to fully raise the arms, and more than ample for bending the body in any direction. If more or less room is needed, larger or smaller pleats can be used. Also by using some type of stiffening cloth in the waistband, enough body is obtained to hold the waistband of the blouse upright permanently in its contour and also hold the blouse 1½ inches above the waistline. Furthermore, elastic could be used in the band, although it is preferred to make the entire garment of the same material so that all of the cloth in the garment will react the same during washing or cleaning.

The above described blouse or shirt construction not only permits arm raising and body bending movements but will return the garment to its original attractive appearance after being expanded by the body movements.

I claim:

1. A garment comprising a plurality of sections having upper and lower parts, said lower parts being contoured by sewn darts, said darts having long longitudinal dimensions and varying transverse dimensions, and waistbands to which the lower edges of said lower parts are sewn, said lower parts of said sections being flat-folded over the adjacent portions of said waistbands along a line connecting the widest transverse dimensions of said darts before said darts are sewn.

2. A garment in accordance with claim 1 in which said darts are substantially triangular and extend from the lower edges of said lower parts.

3. A garment comprising a plurality of sections adapted to be sewn together, a plurality of darts in each of said sections, said darts having long longitudinal dimensions and varying transverse dimensions, some of said darts being substantially diamond-shaped to contour said sections, the lower portions of other of said darts varying

in width to take out excess material in said sections, said darts being sewn axially along the boundaries of their transverse dimensions, and waistbands to which the lower edges of said sections are sewn, the lower parts of said plurality of sections being flat-folded over the adjacent portions of said waistbands along a line connecting the widest of said transverse dimensions of said darts before said darts are sewn.

4. A garment comprising a plurality of sections adapted to be sewn together, a plurality of darts in each of said sections, said darts being tapered over portions thereof and extending to the lower edges of said sections and having a longitudinal dimension and varying transverse dimensions, said darts being sewn axially along the boundaries of their transverse dimensions, and waistbands to which the lower edges of said sections are sewn, the lower parts of said plurality of sections being folded over the adjacent portions of said waistbands along a line connecting the widest of said transverse dimensions of said darts, the boundaries of certain of said darts being diamond-shaped, and the boundaries of certain other of said darts being in part substantially parallel.
